UNITED STATES PATENT OFFICE.

GEORGE W. WOODWARD, OF BROOKLYN, ASSIGNOR TO THE ANSONIA BRASS
AND COPPER COMPANY, OF NEW YORK, N. Y.

LAMP.

SPECIFICATION forming part of Letters Patent No. 417,620, dated December 17, 1889.

Application filed April 15, 1889. Serial No. 307,241. (No model.)

To all whom it may concern:

Be it known that I, GEORGE W. WOODWARD, of Brooklyn, in Kings county, and the State of New York, have invented a certain 5 new and useful Improvement in Lamps, of which the following is a specification.

My improvement relates to that type of central-draft lamps in which is employed a thimble or inner air-distributer that extends 10 from the central-draft tube upwardly some distance above the same and supplies air in jets to the inner surface of the flame.

The improvement consists in a wick-tube having the upper edge of its inner wick tube 15 or shell extended inwardly and a perforated thimble of uniform size from end to end extended into the inner shell, providing an uninterrupted annular air-space between it and the inner shell, the said thimble having a 20 bearing on all portions of the inwardly-turned edge.

In the accompanying drawings, Figure 1 is a central vertical section of the upper part of a lamp embodying my improvement. Fig. 25 2 is a plan or top view of the central portion thereof. Fig. 3 is a side view of a thimble or inner air-distributer.

Similar letters of reference designate corresponding parts in all the figures.

30 A designates the upper part of an oil-reservoir. This reservoir may be made of sheet metal or other material and of any desired form.

B' B² designate two cylindric tubes or 35 shells arranged concentrically, one B' within the other B². These may be made of sheet metal. A wick C, of annular form, is arranged between these two tubes or shells B' B². The inner tube or shell B' serves as a 40 central flue, through which air may ascend to the inner surface of a flame emanating from the wick. Air passes to the outer surface of the flame through an air-distributer D, arranged outside the upper portion of the 45 tube or shell B², and secured, preferably in a detachable manner, in the upper part of the reservoir. The wick C is shown as surrounded by a band or ring E, which may be made of sheet metal.

50 F designates a draw-bar connected with the band or ring E and extending up through

a guide in the upper part of the reservoir, so as to be accessible from the outside of the reservoir. By raising or lowering this draw-bar the wick may be elevated or depressed. 55 The draw-bar may be detachably secured to the band or ring; but this is immaterial to my present improvement.

G designates an inner air-distributer or thimble. It is arranged at the upper end of 60 the inner tube or shell B' of the wick-tube. It may be made of sheet metal. As shown, it is cylindrical and of uniform size from end to end, imperforate at the top, and perforated along the sides. It receives the air ascending 65 through the inner tube or shell B', and distributes this air in jets upon the inner surface of the flame. It is the peculiar combination of this inner air-distributer or thimble G with the inner tube or shell B' of the wick-tube that constitutes my present improvement. The upper end of the inner tube or shell B' is bent or turned inwardly, so as to 70 form a bearing for the inner air-distributer or thimble. In this way the inner air-distributer or thimble may be stayed or maintained in an upright position, and need not be for this purpose provided with any outward projections, and it also provides an uninterrupted annular air-space between the 75 thimble and inner shell of the wick-tube. The manner of sustaining the inner air-distributer or thimble vertically is not material. I have shown a shelf H arranged within the inner tube or shell B' for this purpose and as 80 supported upon a bead b', turned inwardly in the said inner tube or shell.

The inwardly-turned upper edge of the inner tube or shell is very advantageous. It bears wholly upon the thimble and tends to 85 catch oil running down the body or thimble and conduct it into the wick-tube, instead of allowing it to flow down through the central air-passage. It materially reduces the liability of any débris from the wick falling through 90 the central air-passage. The wick cannot catch upon the upper edge of the inner tube or shell while being lowered. Outward projections upon the inner air-distributer or thimble are rendered unnecessary. All air 95 ascending the central air-passage will be caused to pass into the inner air-distributer 100

or thimble. The wick will be left free and loose at the top.

What I claim as my invention, and desire to secure by Letters Patent, is—

5 In a central-draft lamp, the combination of a wick-tube having the upper edge of its inner tube or shell extended inwardly, and an air-distributer or thimble perforated along its sides and of uniform size from end to end, the

said thimble extended into the inner shell, leaving an uninterrupted annular air-space between it and the inner shell, the said thimble having a bearing on all portions of the inwardly-turned edge, substantially as specified.

GEORGE W. WOODWARD.
